(57) **CLAIM**

I claim the ornamental design for an architectural panel, as shown and described.

DESCRIPTION

FIG. 1 is an upper front right perspective view of a first embodiment architectural panel showing our new design;
FIG. 2 is a front elevational view thereof;
FIG. 3 is a left side elevational view thereof,
FIG. 4 is a right side elevational view thereof,
FIG. 5 is a top plan view thereof; and
FIG. 6 is a bottom plan view thereof.

FIG. 7 is an upper front left perspective view of a second embodiment architectural panel showing our new design;
FIG. 8 is a front elevational view thereof;
FIG. 9 is a left side elevational view thereof,
FIG. 10 is a right side elevational view thereof,
FIG. 11 is a top plan view thereof; and,
FIG. 12 is a bottom plan view thereof.

The broken lines in the drawings represent portions of the architectural panel that form no part of the claimed design.
